INCINERATOR WITH COMBUSTION AIR FEEDING MEANS FOR UNDERGROUND USE

Earl W. Edwards, South Pasadena, Calif.

Application April 20, 1945, Serial No. 589,354

2 Claims. (Cl. 110—18)

1

This invention relates to an incinerator, particularly to a type of incinerator that is adapted for household use.

Incinerators for this purpose are usually constructed of "cement" or concrete and stand in an upright position, the charge being supported on a grate, below which a draft inlet is located so that the air for combustion passes up through the entire mass of the charge. Such incinerators usually include a short stack to increase the draft through the body of the burning charge. The amount of draft induced by the stack, however, is relatively small. Furthermore, the resistance of the mass of the burning charge is considerable, and the result is usually that in the operation of most incinerators of this type, the combustion is incomplete and is not completed in the stack. Hence, such incinerators smoke considerably, and sometimes they become a nuisance on this account.

One of the objects of this invention is to provide an incinerator having a construction which will overcome these disadvantages, and in which ample flow of air for combustion is induced, and at the same time providing a construction that will cause the mass of refuse to burn on its outer surface, and so that the air for combustion passes directly over the surface that is ignited; in this I avoid the considerable resistance to the flow of the air that is inherent in the operation of an upright incinerator where the air passes up through the entire mass of the charge.

The upright type of incinerator referred to above is unsightly and takes up considerable space above the ground. On this account it is usually located inconspicuously in the back yard or in the service yard back of the main portion of the yard, and usually its owner endeavors to screen it from view by a trellis, lattice work, or in some other way.

One of the objects of this invention is to provide an incinerator, the body of which is substantially concealed in the ground, that is to say, the body is below the ground level; also to provide means whereby the stack or stacks for the gases of combustion may be removed when the incinerator is not burning refuse, thereby enabling the presence of the incinerator to be scarcely noticeable.

Another object of the invention is to accomplish the above indicated purposes, including the provision of ample means for admitting air for combustion to the burning refuse and at the same time providing effective means for excluding rain water from the fire pot or chamber within the

2

body of the incinerator in which the refuse is consumed.

Another object of the invention is to provide construction for the cover portion of the incinerator that will facilitate the placing of the charge of refuse in the same.

Another object of the invention is to provide an incinerator of this type with a movable lid having an improved hinge construction, particularly adapted for supporting a lid on a concrete or cement body.

Further objects of the invention will appear hereinafter.

The invention resides in my novel method of burning the charge and also consists in the novel parts and combinations of parts to be described hereinafter, all of which contribute to produce an efficient incinerator.

A preferred embodiment of the invention is described in the following specification, while the broad scope of the invention is pointed out in the appended claims.

In the drawing:

Figure 1 is a perspective of an incinerator embodying my invention.

Figure 2 is a vertical section taken through the incinerator illustrated in Figure 1, passing on its longitudinal axis, and up through the axes of the stacks that are represented broken away.

Figure 3 is a fragmentary view, and a vertical section illustrating the manner in which a bonnet employed with the chimney or stack of the device is made to exclude water from the smoke outlet when the stack has been removed. This view shows a short portion of a cover plate of the incinerator, and shows the bonnet in cross-section.

Figure 4 is a vertical section and is also a fragmentary view taken about on the line 4—4 of Figure 1. This view particularly illustrates the construction of the hinge joint I employ for mounting the lid or movable cover portion of the cover.

Figure 5 is also a fragmentary view, and is a vertical cross-section taken on the line 5—5 of Figure 2, particularly illustrating an air duct associated with the lid or main cover portion.

Figure 6 is a fragmentary view, and is a vertical section taken in vertical plane through the stop arm for holding the lid open, but illustrating the lid when in its open position.

Referring more particularly to the parts, I indicates the incinerator body which is preferably of box form and constructed of "cement" or concrete. This body is elongated on a substantially

horizontal axis, and is preferably substantially buried in the ground so that practically all of the body except its cover portion 2 is located below the ground level 3.

The incinerator illustrated is of a duplex type, that is to say, it presents a construction which enables the charge to burn in two zones of combustion arranged so that the gases of combustion or smoke passing from the incinerator body will rise through two stacks or chimneys 4 located toward the ends of the body. These stacks are supported on two end slabs 5 preferably of concrete that form the two end portions of the cover wall 2, and each of these slabs carries a smoke outlet 6 over which one of the two stacks 4 are mounted.

In order to center the stacks and hold them in position, I prefer to provide a small flange 7 that extends upwardly around each of the openings 6, and each stack has a bell-mouth 8 at its lower end where the diameter of the stack is enlarged to enable it to fit closely over the flange, substantially as shown. This flange 7 may be made as long as desired so that a good joint connection is made for the foot of the stack that will prevent its being dislodged, or blown over by the wind.

In order to assist in holding the slabs 5 in position after they are set in place, I prefer to provide each of them with a transverse rib 9 that extends all the way across between the side walls, and projects downwardly so as to form a shoulder abutting against the inner face of the end wall.

Between the two slabs 5 I provide a middle section or lid 10 which is adapted to be lifted or swung up in order to facilitate placing refuse in the fire pot. While this lid 10 can be constructed of "cement" or concrete, if it is desired to make it of light weight, I construct it of sheet metal pressed in dies to give it substantially the form illustrated in Figure 2. Its side edges rest on the upper edges of the side walls of the fire pot.

In order to form a waterproof joint between the ends of the lid 10 and the adjacent edges of the slabs 5, I prefer to form the ends of the lid 10 with upwardly offset flanges 11, the outer ends of which terminate in downwardly projecting tongues 12, and these tongues are received in shallow gutters or grooves 13 that extend all the way across the slabs 5, so that their ends are open. In this way perfect drainage is attained regardless of whether either the front or rear wall of the incinerator is slightly elevated with respect to the other.

At an intermediate point between the stacks 4 and preferably at about the middle of the lid 10, I provide means for admitting atmospheric air to support the combustion of the charge of burning refuse within the incinerator. For this purpose I provide an opening or air inlet 14 in the cover 10 (see Figure 2) at the edge of which the material of the lid is projecting upwardly to form a low flange or coaming 15. This coaming excludes drainage water flowing across the upper side of the lid. This admits the air for combustion to the interior of the incinerator just below the lid and above the level of the charge of burning refuse.

In order to exclude rain water falling onto the lid I provide a baffle 16 in the form of a horizontal plate of greater area than the air inlet 14, which is disposed slightly above the upper edge of the coaming 15 so as to leave an effective inlet open-

ing 17 of considerable area. This baffle plate 16 is held in a fixed position, being attached rigidly to an upwardly off-set tongue 18 that is integral with the body portion 19 of a metal strap. This strap is welded or riveted to the upper face of the lid 10, and its outer end adjacent the hinged edge of the lid is formed with an upright tongue 20, the purpose of which is to enable the strap to hold the lid 10 in an open position as indicated in Figure 6. For this purpose the outer end of the tongue 20 is preferably formed with an off-set tip, or foot 21a to rest upon the ground. If desired this tongue may be formed so as to engage the side of the incinerator to hold the lid upright, and in a position of equilibrium.

The lid 10 is preferably provided with a pair of hinge connections 22 which are also preferably constructed of strap metal. Each hinge connection includes a strap metal body welded or riveted to the upper side of the lid 10, and the outer end of each of these bodies 23 is bent around to form an open pintle of substantially cylindrical form. This pintle lies in a half round socket 25 formed in the upper edge of the wall of the body opposite the hinge member 22. In order to enable the pintle to be of substantial size, the upper edge of the body at the point where the hinges are placed, is preferably formed with an outwardly projecting abutment 26 in which the half round socket 25 is formed. The advantage of this type of hinge is that it does not necessitate attaching any metal part to the cement wall to act as a support for the movable hinge member. It is merely necessary to provide the abutments with the half round, or cylindrical, sockets 25 in their upper faces.

In Figure 2, 27 indicates the charge of refuse. The upper surface 28 of this charge should be a sufficient distance below the cover 2 to insure ample area for enabling combustion air passing in at the inlet 14 to find its way to the stacks 4, which operate as uptakes to develop a draft through the action of gases within the stacks. In operating the incinerator, after it has been charged, the lid should be lifted by means of the handle 10a and the refuse at the upper surface 28, and preferably below the end portions of the lid 10, should be ignited with a match or other means. In other words, the ignition would take place at some point such as the points 29 between the air inlet 14 and the stacks. As the burning of the charge progresses the stacks 4 will become heated and assist in maintaining considerable temperature in the gases of combustion that are passing up through the stacks. This will induce a considerable draft and low pressure in the zones of combustion in the vicinity of the points 29, or thereabout, so that a considerable quantity of air will pass in through the air inlet 14. This air supply is more than sufficient for effecting complete combustion of the burning material, largely by reason of the fact that the material burning does not consist of a large mass of material through which the air must pass, but is merely a mass of material, the surface of which is burning. For this reason there is an excess amount of air for combustion and hence this incinerator will develop very little or no smoke when in operation.

Furthermore, I believe that the incinerator will operate more efficiently if the underside of the lid 10 is provided with air ducts 30 leading from the air inlet 14 in a single pass to a point below the slabs 5. These ducts are in the form of channels the flanges of which are welded or

riveted to the underside of the lid 10, and they are open at their ends. And the bottoms, that is, the walls of these ducts toward the refuse, are provided with a series of perforations 31. Of course there is always a considerable flow of air in the ducts 30, and this air tends to become heated by the walls of the ducts. By reason of the velocity of this air current flowing outwardly through these ducts, a considerable amount of air and smoke is entrained in an upward direction where the duct delivers into the stack and a slight amount may be entrained through the perforations 31. This tends to reduce the pressure in the spaces at about the points 32 just above the upper surface of the charge and below the ducts 30. In this way passage of incoming air downwardly under the inlet 14 is induced, and down to a level below the ducts 30 and adjacent to the burning surface of the mass of the charge. However, the ducts function satisfactorily if not provided with perforations.

If desired the stacks 4 may be provided with air inlets 33 located at any desired level for admitting additional air for promoting combustion. In this way complete combustion of gaseous material carried in the smoke is assured. Near the upper end of each stack 4, a wire screen, not illustrated, would be provided to conform with city fire ordinances.

When the stacks 4 are in place their upper ends are covered by "umbrellas" or bonnets 34. These bonnets are of substantially conical form and provided on their inner sides with a plurality of spring-fingers 35 (see Figure 3) that extends downwardly. When the incinerator is not in use, the stacks 4 can be removed if desired and at this time the bonnets 34 are applied at the smoke outlets 6. For this purpose each finger 35 has an off-set portion 36 formed between two shoulders 37 and 38, the latter of which is formed at an arc-shaped tip 39 to facilitate inserting and pulling the fingers out of the stacks or out of the opening 6 in which they would be set when the stacks have been removed. These bonnets effectively prevent any rain water from passing down. The flanges 7, of course, prevent any drain water flowing across the upper sides of the slabs 5 from descending through these openings.

Many other embodiments of this invention may be resorted to without departing from the spirit of the invention.

I claim as my invention:

1. In an incinerator, the combination of a body having a chamber open on its upper side, elongated along a substantially horizontal axis, to receive the charge of refuse to be burned, a substantially flat cover wall closing the upper side of said body adapted to form a substantially level surface on its upper side substantially flush with the ground level, said wall including end portions closing the upper side of said body at the ends thereof, and each of said end portions having an outlet therein for smoke, said cover wall also including a lid extending over said body between said end portions of the cover; said lid having an air-inlet at a point substantially midway between said outlets; air-ducts located at the under side of the lid extending in a substantially

straight line from a point near the said air-inlet to points adjacent the said smoke outlets, respectively, operating to supply heated air to the lower end of the stacks to increase the combustion, and draft up the stacks; said increased draft operating to induce an increased inflow of air for combustion at said air-inlet.

2. In an incinerator, the combination of a body adapted to be buried in the ground, having a chamber open on its upper side, and elongated along a substantially horizontal axis, to receive the charge of refuse to be burned; a substantially flat cover wall closing the upper side of said body, adapted to form a substantially level surface on its upper side substantially flush with the ground level, said cover wall including end portions closing the upper side of said body at the ends thereof, and each of said end portions having an outlet therein for smoke, said cover wall also including a lid extending over said body between said end portions of the cover and adapted to be raised to enable refuse to be charged into the said body; said lid having an air-inlet located at a point substantially midway between said outlets operating to admit the air for combustion just below the level of the lid and above the level of the charge to be burned, stacks mounted respectively over said smoke outlets operating to induce a draft to draw the air for combustion through the said air inlet, and air-ducts attached to the under side of the lid, said air-ducts extending from a point near the said air-inlet to points adjacent the said smoke outlets, respectively, and operating to supply heated air to the lower end of the stack and increase the draft in the stack, said increased draft operating to induce an increased inflow of air for combustion at said air-inlet.

EARL W. EDWARDS.
